REFLECTOR

William O. Spieth, Cleveland Heights, Ohio

Application December 12, 1940; Serial No. 369,786

3 Claims. (Cl. 88—82)

This invention relates to a light reflecting device and is particularly adapted for use in signs, markers, and similar devices, which are intended to receive light from the lamps of an on-coming vehicle or the like and to return this light to the driver.

An object of the invention is to provide an improved reflector having high visibility.

Another object is to provide an improved reflector which will return light directed toward it throughout an extremely extensive zone.

Another object is to provide an improved reflector which will be relatively immune to breakage.

Another object is to provide an improved reflector in which the parts may be assembled at normal atmospheric temperatures.

Another object is to provide an improved reflector which may be easily and economically manufactured.

Another object is to provide an improved reflector which will not be subject to deterioration from exposure to the weather.

Another object is to provide an improved reflector which may be readily assembled into signs, markers, and the like.

Another object is to provide an improved reflector which will be neat and attractive in appearance.

Other objects will hereinafter appear.

The invention will be better understood from the description of several practical embodiments thereof, illustrated in the accompanying drawing, in which:

Figure 1 is a front elevational view of a sign, such as may be used for displaying the street number of a building, the various characters of the sign each including a number of reflectors embodying the invention;

Figure 2 is an enlarged sectional somewhat diagrammatic view of the lens and reflector portion of the device;

Figure 3 is an enlarged elevational view of one of the characters of the sign of Figure 1;

Figure 4 is a cross-sectional view of the component parts making up the character of Figure 2 in disassembled relation;

Figure 5 is a view of the parts of Figure 3 in assembled relation, being a sectional view taken on the line V—V of Figure 3, immediately after the assembly of the parts;

Figure 6 is a view similar to Figure 5 showing the parts in final assembled relationship;

Figures 7 and 8 are sectional views similar to

Figure 5, of three other modifications embodying the invention;

Figure 9 is a view similar to Figure 4 of another embodiment of the invention, showing the parts in disassembled relation; and

Figure 10 is a transverse sectional view of the parts of Figure 9 in assembled relation.

Reflectors are used extensively for various kinds of signs and similar devices, such as highway markers, danger signals, house numbers, advertising signs, as safety devices on vehicles, and the like. These reflectors have taken a number of shapes, some of them being formed into large, relatively flat surfaces, and others being composed of a number of small separate circular, prismatic, or other shaped reflectors.

They also have been composed of a number of materials such as, in their simplest form, being merely sheet metal provided with a reflecting surface which may or may not be colored, and in other forms consisting of glass plates, prisms, and the like, provided with reflecting coatings such as of quicksilver, with metallic reflectors placed behind them.

All prior reflectors with which I am familiar are possessed of certain inherent disadvantages.

When new, they generally reflect light fairly well, providing the light comes from nearly normal to the surface to which they are attached or in which they are formed.

With exposure to the weather, however, they become dim in time. This is due, doubtless, to the corrosion or tarnishing of the reflector material.

When simple metal reflectors are used, they are, of course, exposed fully to the weather. When the reflectors are covered by transparent material, they are somewhat protected, but moisture and the like attacks them from the rear, and differences in expansion and contraction loosen them so that it may work in around the edges and in time destroy their reflecting surfaces.

Moreover, as above pointed out, all prior reflectors, are effective only through a relatively limited angle, being most visible when light is thrown on them in a direction normal to their surface and when the observer is also in a position substantially normal to their surface. With most prior reflectors, when the light or observer moves only a few degrees to one side or the other, the brilliancy of the reflected light is lost.

In the reflectors illustrated in the accompanying drawing, light may be reflected throughout a wide angle—throughout a zone of substantially 180° in extent—in all directions, as the optical

characteristics of the reflector do not vary as the position of the light and observer move throughout this zone.

This will be better understood by a reference to the diagrammatic illustration of Figure 2.

In this figure is illustrated a transparent lens, indicated generally at 1, which lens consists of two concentric spherical surfaces 2 and 3, each extending throughout a spherical zone of one hemisphere, the surfaces being joined by a plane surface 4. The surface 3 is provided with a reflector or speculum shown as a hemispherical metal cup 5, which fits closely against this surface.

If, now, a beam of light, consisting of parallel rays 6a, 6b, and 6c be considered as approaching the reflector from any direction, it will be noted that this beam impinges on spherical surface 2 in such a manner that one ray 6a strikes the surface of the lens exactly normal to its surface and that rays 6b and 6c, equally distant therefrom, strike this surface at a relatively slight angle from the normal. Ray 6a, therefore, is not deflected in any manner from its course, but continues straight through the lens to the speculum 5, being normal to this surface, and is reflected back along the same line on which it approached the reflector.

Rays 6b and 6c, however, are refracted slightly toward the path of ray 6a, strike the speculum 30 at a slightly oblique angle, so that when returning to the outer air, they are refracted to be somewhat convergent, as indicated by the arrowheads applied to ray 6b.

If the radii of surfaces 2 and 3 were such that the speculum 5 lay exactly at the focal distance from the surface 2, the rays would all focus at one point and return substantially along the paths they had followed in reaching the reflector.

I find that this arrangement gives a very brilliant spot of light of very minute size. Also its brilliancy is visible only with the eye substantially in alignment with the source of light. While such an arrangement would present doubtless the maximum efficiency, it is impracticable for the purpose for which the reflector is intended, in that these reflectors are mainly observed by drivers of vehicles, the driver's eye being substantially above and generally somewhat to the side of the source of illumination, namely, the car's headlights.

I find, therefore, that the surface 3 must be one defined by a radius greater than that of surface 2, but less than that to the focal distance which would be defined by the surface 2.

In using for the transparent material of the lens, the transparent plastic known as "Lucite," or with glass, I find that the radius of surface 2 should be approximately $\frac{3}{4}$ the radius of surface 3.

This ratio would doubtless vary somewhat with the index of refraction of the transparent material used, but this proportion seems to be satisfactory for a number of the materials now available including, as well as some of the plastics, glass.

I find that the relation of the radii of the two spherical surfaces is somewhat critical, and that brilliancy of reflection is lost as these radii approach each other, while, as above indicated, the point at which the brilliancy may be observed becomes limited as the radius of surface 3 approaches the focal distance of the surface 2.

To utilize the characteristics described in conjunction with the diagrammatic illustrations, I

have shown a number of possible embodiments of the invention.

Figures 1, 3, 4, 5, and 6 show one manner in which it may be applied.

5 In these figures is shown a series of numerals such as may be used for a street number sign, to be placed before a building, and, as illustrated, the sign consists of four panels (7, 8, 9, and 10) mounted in a rectangular frame 11, which carries 10 at the top a single large circular reflector 12.

On the face of each panel is delineated a numeral consisting of a projecting body provided with a number of circular reflector buttons, the projecting body of the panel 7 carrying the numeral 1 being the one chosen for illustration in the succeeding figures.

The panel itself is shown as a small rectangular piece of flat material, such as sheet metal, being cut through to provide an opening substantially the shape of the character to be applied.

25 This numeral is outlined by means of a body portion 13 provided with a plurality of circular apertures 14 in which are mounted the reflector lenses, visible from the front of the sign. A backing or covering block is arranged to secure these reflector lenses in place and to clamp the body 13 to the panel 7 as well as to seal between itself and the body the specula for the several reflecting elements, as will be hereinafter described.

The body 13 has shoulders 15 adapted to rest upon the front face of the panel 7, and within these shoulders is a flange 16 which projects through the opening in the panel.

30 The lens consists of a piece of transparent material having a spherical surface 2 of smaller radius and a spherical surface 3 of larger radius, corresponding to those described in conjunction with the diagram.

35 The two spherical surfaces are connected by a stepped surface, providing a recess 17 and a flange 18, which are arranged to interlock closely with a flange 19 and recess 20, respectively, formed on the inner side of the body 13. The speculum is a hemispherical metal cup 5, which, as above indicated, has a highly reflective inner surface. The speculum may conveniently be a stamping made from suitable sheet metal.

40 The backing block 21 is provided with a hemispherical recess 22 to receive the speculum and with a groove 23, which constitutes a mortise capable of receiving flange 16 in the manner of a tenon, to hold the parts together.

45 Outwardly beyond this recess, a flange 24 is arranged to bear upon the rear side of panel 7.

50 These parts are assembled as most clearly shown in Figures 4, 5, and 6.

55 While, of course, I may use any satisfactory transparent material for the lens, and the same or any other material for the body 13 and block 21, I prefer to make these parts of molded plastic, and preferably of the same or similar plastic. If they be made of such material they may be permanently united by means of either a cement or solvent.

60 First positioning these parts as illustrated in Figure 4, the interlocking surfaces of body 13, block 21, and the recess 17 and flange 18 of the lens are coated with a suitable adhesive or suitable solvent, the parts pressed together into the position illustrated in Figure 5, and held for a short time until the cement hardens or the solvent evaporates.

65 With materials which may be united by solvent, the contacting surfaces of these materials, in effect, fuse into each other, so that upon comple-

tion, the article assumes the characteristics illustrated in Figure 6, in which the body, lens, and backing block have become a single integral block of material, completely encasing the speculum and clamping itself to the panel 7 so that it may not be removed therefrom without destruction or deformation of either the block of material or the panel.

The speculum, being thus encased, is absolutely sealed away from the weather, moisture and the like, and protected against deterioration so long as the encasing block remains unbroken. Its useful life as a reflector is therefore infinite. It will also be noted, that no heat need be applied, and discoloration which might take place if the transparent material were molded about the metal is thus avoided.

In the case of the single reflector 12, shown on the sign, the body and backing block are circular, the body being indicated at 13a, but it will be appreciated that the cross-section of the parts of this reflector will be identical, wherever the section is taken, to the illustrations 4, 5, and 6, and also, that the numerals themselves might be formed of single reflectors made in this manner.

Figure 7 shows a modification in which the supporting panel and backing block are made integrally in a single piece of molded plastic material or the like, indicated generally at 107, and provided on one face with hemispherical recesses 122 and with mortise-like recesses 123 which receive the depending flange 116 of blocks 113.

The lens used in this structure is substantially identical to that above described, having spherical surfaces 102 and 103, and a hemispherical speculum 105. It will be appreciated that the body 113 is, as in the first embodiment, sealed to the backing body and panel by means of a suitable adhesive or solvent, and so likewise seals in the speculum.

In Figure 8, the backing block 221 is provided with recesses 223 to receive the flange 216 of the body 213, these two being sealed together and to the lens so that they totally enclose the speculum 205.

These parts are adapted to be mounted in a wooden panel 207, the backing block fitting into a recess cut into this panel and the entry of the entire character being limited by the shoulders 215 which rest upon the front face of the panel. The space within the panel and about the backing block is filled with a suitable cement or adhesive material 210, such for instance, as the cellulose composition now known as "plastic wood," to retain the character firmly in place.

In Figures 9 and 10, still another embodiment of the invention is illustrated, in which the reflector consists of only 3 parts, the lens, the backing block and the speculum.

Here again, the radius of the exposed surface of the lens 302 is related to the radius of the reflector surface 303 in a ratio such as disclosed in conjunction with the diagram of Figure 2.

The backing block 321 has spaced annular flanges 323 and 324 between which is received an annular flange 306 formed integrally with the lens and by which the parts are sealed together. The lens has a peripheral flange 315 formed integrally therewith, between which and the flange 324 the edges of the panel 307 may be gripped.

While the specula shown are each approximately a hemisphere, it will be apparent that they could be limited to a zone somewhat less in ex-

tent, which will correspondingly limit the angle through which the maximum brilliance of the device is observable, particularly when the reflectors are to be used in places where it is not desired that the reflected light be seen through a wide angle. The angle through which it may best be seen will be approximately that defined by the speculum and thus readily may be determined.

Also, while the lens is shown extending into contact with the entire surface of the speculum, these might be spaced apart. For instance, the lens might terminate with a plane surface parallel to the background and passing through the center of curvature of the front of the lens. In any event, however, the front of the lens, in cross section, should be a circular arc and be concentric with the reflecting surface of the speculum.

While I find that the transparent plastics produce a particularly suitable reflector which is unbreakable, and which is not seriously impaired by surface scratches or the like, it will be apparent that the lens portion of the device may well be made of any transparent material such as glass, and that with such a material, the parts would be secured to this material by adhesion rather than by fusing with the glass itself. However, adhesive on the interlocking flanges shown produces a very effective seal and adequately protects the speculum.

While I have described the illustrated embodiments of my invention with some particularity, obviously many other modifications and variations will readily occur to those skilled in the art to which they appertain. I do not therefore limit myself to the precise details shown and described, but claim as my invention all embodiments, modifications and variations within the scope of the appended claims.

I claim:

1. A reflector comprising a lens defined by two concentric spherical-zone surfaces of different radii, a spherical-zone shaped speculum adjacent the surface of the lens of larger radius, a back block receiving said speculum, a body having an aperture through which the spherical zone of smaller radius of the lens projects, interfitting projections between the body and the block, and securing means sealing the body to the block and the body to the lens.

2. A reflector comprising a lens defined by two concentric spherical-zone surfaces of different radii, a spherical-zone shaped speculum adjacent the surface of the lens of larger radius, a back block receiving said speculum, a body having an aperture through which the spherical zone of smaller radius of the lens projects, interfitting projections between the body and the block, and securing means sealing the body to the block and the body to the lens, and a support held between the body and the block.

3. A reflector comprising a lens defined by two concentric spherical-zone surfaces of different radii, a spherical-zone shaped speculum adjacent the surface of the lens of larger radius, a back block receiving said speculum, a body having an aperture through which the spherical zone of smaller radius of the lens projects, interfitting projections between the body and the block, and adhesive sealing the body to the block and the body to the lens.

WILLIAM O. SPIETH.
